United States Patent Office

Des. 228,807
Patented Oct. 23, 1973

228,807

OPAQUE PROJECTION VIEWER

Alphonse P. Cinque, 65 Earle Ave.,
Lynbrook, N.Y. 11563

Filed Nov. 22, 1971, Ser. No. 201,255

Term of patent 14 years

Int. Cl. D16—03

U.S. Cl. D61—1 N

FIG. 1

FIG. 2

FIG. 3

FIG. 4

FIG. 5

FIG. 6

FIG. 1 is a perspective view of an opaque-projection viewer showing my new design;

FIG. 2 is a front elevational view thereof;

FIG. 3 is a top plan view thereof;

FIG. 4 is a bottom plan view thereof;

FIG. 5 is a left side elevational view thereof the right side being a mirror image thereto, and

FIG. 6 is a rear elevational view thereof.

I claim:

The ornamental design for an opaque projection viewer, substantially as shown and described.
